UNITED STATES PATENT OFFICE.

GEORGE W. VAN ALSTINE, OF LOS ANGELES, CALIFORNIA, ASSIGNOR TO
THE ANTISEPTIC APPLIANCE COMPANY, OF SAME PLACE.

ANTISEPTIC DEVICE FOR SOUND-TRANSMITTER MOUTHPIECES.

SPECIFICATION forming part of Letters Patent No. 635,209, dated October 17, 1899.

Application filed April 6, 1899. Serial No. 712,004. (No model.)

To all whom it may concern:

Be it known that I, GEORGE W. VAN ALSTINE, residing at Los Angeles, in the county of Los Angeles and State of California, have 5 invented a new and useful Antiseptic Device for Sound-Transmitter Mouthpieces, of which the following is a specification.

The object of my invention is to provide superior means for affording protection against 10 the transmission of infectious and other diseases through the medium of mouthpieces of sound-transmitters—such, for instance, as the mouthpieces of telephones and speaking-tubes.

15 It is an object of my invention to provide means for catching all impurities which may be blown into the mouthpiece by the user and to hold such impurities out of the way of any danger of infection to any user and to prevent 20 the impurities from coming into contact with the mouthpiece, the whole to be readily removed from the mouthpiece and destroyed, being of such an inexpensive character that frequent renewals will be acceptable from an 25 economic point of view as well as from hygienic considerations.

The accompanying drawings illustrate my invention.

Figure 1 is a perspective view of a telephone-transmitter provided with my improvement. Fig. 2 is an axial section of the mouthpiece of the same. Fig. 3 is a front view of a transmitter-mouthpiece provided with my invention. Fig. 4 is an axial section of a modified 35 form in which the cup is provided with an absorbent felt having a central hole. Fig. 5 is an axial section of a cup which is not reinforced.

A indicates the sound-transmitter mouth-piece.

1 indicates a lining composed of a cup formed of antiseptic gauze. The antiseptic gauze which is preferred is known to the trade as "bichromid" gauze, and the purpose of 45 using this gauze is to provide for the instantaneous destruction of any living microbes or germs which may come into contact with the lining. This lining is fastened to the transmitter by any suitable means. For instance, 50 it may be fitted to the transmitter so that it

will be held therein by friction, or a rim-piece B, of metal, with spring-tongues b may be applied. Said cup forms a receptacle inside the mouthpiece. The antiseptic-gauze bottom of said cup forms a screen inside the mouthpiece 55 extending transverse the mouthpiece at a distance from the rim of the mouthpiece, thereby forming a protection for the interior of the mouthpiece and also for the telephone-diaphragm to prevent any foreign particles from 60 being injected into the mouthpiece beyond the bottom of the cup, the cup being thus designed to perfectly protect the mouthpiece and the telephone-diaphragm and also to destroy the germs which may come into contact 65 with the antiseptic gauze and to hold them out of the way. In this relation I will state that an object which is attained by my invention is perfect protection accomplished with extreme simplicity and cheapness, so that 70 while the cup may be allowed to remain in the mouthpiece and will serve as a protection therefor for any desired length of time and may be effective as an antiseptic for a number of days still the simplicity and cheap- 75 ness of the device are such that it may, without objection as to cost or convenience, be renewed every day or oftener if deemed necessary. If not removed, the foreign matters which may have been injected into the cup 80 are held in the least objectionable manner, so that there is no danger of coming into contact with or endangering any person who may subsequently use or approach the mouthpiece of the telephone. 85

By my invention I do not depend upon the odors or affluvia which arise from the disinfectant to perform the disinfecting office, but I provide an antiseptic-gauze cup which prevents the retention of any living germs, the 90 germs which are thrown into the mouthpiece being acted upon by the antiseptic contained in the antiseptic gauze.

My invention is to be distinguished from any of the devices in which it is proposed to 95 retain a body of fluid antiseptic, for the reason that such devices are more cumbersome and expensive than would serve my purpose.

My invention is also to be distinguished from any device comprising a diaphragm ex- 100

tending across the rim of the mouthpiece, for in such appliances the impurities blown from the mouth are intercepted outside the mouthpiece and are liable to adhere to the diaphragm and be there held in position close in front of the lips of the user of the mouthpiece and without any protection to prevent the lips from coming into contact with such impurities. In such appliances it is necessary that the antiseptic substance shall not be allowed to become innocuous; otherwise the diaphragm becomes a menace by holding the impurities, microbes, and bacilli closer to the lips than would be the case if the diaphragm were dispensed with. By my invention this difficulty is avoided, and in case the gauze cup were to remain in place so long as to lose its antiseptic qualities the impurities, &c., will be held inside the cup out of the way of the lips until the cup is removed.

2 indicates a reinforcing-piece formed of antiseptic gauze, which is preferably applied at the bottom of the cup. The reinforcing-piece is preferably of finer gauze than the body of the cup.

3 indicates a porous ring, preferably of felt, saturated with a suitable antiseptic substance. This and the reinforcing-piece may be omitted, if desired.

30 Different substances may be used, as desired, for saturating the felt and the gauze. For example, the gauze may be saturated with a percentage solution of corrosive sublimate, known to science to be both safe and effective, and the felt may be saturated with the same, or it may be saturated with the pure essential oils or their active principles, such as thymal, menthol, eucalyptol, or any other well-known antiseptic or any well-known combination of antiseptics which may be found suitable for the purpose. The felt is ordinarily omitted, but when used is preferably interposed between a reinforcing member 6 and the bottom of the cup, thus to form a chamber between the reinforcing member and the bottom of the cup in order to afford a more perfect guard against any particles of food, sputum, or other substance which might be blown from the mouth into the instrument. At the same time the gauze cup and the reinforcing member do not interfere with the transmission of sound. The porous ring forms a retainer for a larger quantity of the antiseptic substance, so that air inside the mouthpiece is constantly impregnated with germ-destroying substance, the essential oils affording an agreeable and wholesome odor.

The rim for holding the gauze in place is preferably made of a ring B, of thin sheet metal, which tapers to conform to the inside

of the rim of the mouthpiece, while the spring-tongues b extend outward over the mouth of the mouthpiece to clasp the mouthpiece. The tongues can be bent to conform to different-sized mouthpieces, and the inner ring b' will cover the edge of the gauze cup, thus avoiding any danger of accidental displacement.

In practical use the lining should be renewed from time to time, as may be required, for the purpose of absolute cleanliness and safety. The lining may be removed and replaced with new every day or oftener in cases where it is found desirable to renew so frequently. Where the mouthpiece is not subject to infection, the lining may remain for a greater length of time, and in case the mouthpiece is used by a consumptive or other persons with infectious or contagious disease the lining should be immediately removed and replaced with new.

The cup forms a receptacle for the particles which may be blown from the mouth of the person using the mouthpiece and the particles will not come in contact with the walls of the mouthpiece, but are removed by removing the lining, as above set forth. When the lining is removed, it will be burned or otherwise destroyed.

The ring and reinforcing member can be fastened to the cup member by any suitable means.

The starch of the gauze ordinarily affords sufficient binder for this purpose under the pressure applied in molding the cups.

Now, having described my invention, what I claim as new, and desire to secure by Letters Patent, is—

1. In a sound-transmitter mouthpiece, a detachable cup formed of antiseptic gauze and inserted into the mouthpiece to form a receptacle in the mouthpiece with its bottom transverse said mouthpiece and forming a shield inside the same.

2. In a sound-transmitter mouthpiece, a detachable cup formed of antiseptic gauze and inserted into the mouthpiece to form a receptacle in the mouthpiece with its bottom transverse the mouthpiece and forming a shield inside the same; and a ring of felt at the bottom of said cup.

3. A detachable lining for a sound-transmitter mouthpiece consisting of a cup formed of antiseptic gauze; a ring of porous material saturated with a suitable antiseptic substance inserted in the cup; and a retainer of antiseptic gauze over the antiseptic felt.

GEORGE W. VAN ALSTINE.
